UNITED STATES PATENT OFFICE.

AUGUST SUNDH, OF YONKERS, NEW YORK, ASSIGNOR TO OTIS ELEVATOR COMPANY, OF JERSEY CITY, NEW JERSEY. A CORPORATION OF NEW JERSEY.

CONTACT-HOLDER.

1,083,418.

Specification of Letters Patent.

Patented Jan. 6, 1914.

Application filed March 25, 1908. Serial No. 423,172.

To all whom it may concern:

Be it known that I, AUGUST SUNDH, a citizen of the United States, residing at Yonkers, in the county of Westchester and State of New York, have invented a new and useful Improvement in Contact-Holders, of which the following is a specification.

My invention relates to electric switches, and one of its objects is the provision of simple and efficient means for retaining contacts in a holder with a tight fit.

A further object of the invention is the provision of a contact holder which will effect a wedging of the contact in the holder with a tight fit when used in an electric switch.

Other objects of the invention will appear hereinafter, the novel combinations of elements being set forth in the appended claims.

In the accompanying drawings, Figure 1 represents a plan view of one form of my improved contact holder, with a contact in place therein; Fig. 2 is a side elevation of a complete electromagnetic switch, showing the application of my invention; Fig. 3 is a front elevational view of a modified contact holder, with a contact therein; Fig. 4 is a side view of fixed and movable contacts and holders therefor, certain parts being shown in section; Fig. 5 is a plan view of a fragmentary portion of Fig. 4; Fig. 6 is a front elevational view of another modified contact holder; Fig. 7 is a side elevational view of a multiple switch, and is similar to Fig. 2; Fig. 8 is an enlarged fragmentary view of an electric switch comprising a plurality of contact holders; Fig. 9 is a side view of still another modification of a contact holder; Fig. 10 is a transverse sectional view of Fig. 9; Fig. 11 is a view similar to Fig. 4, and shows the contact holder of Fig. 9 with the clamp omitted; Fig. 12 is a transverse sectional view of Fig. 11; Fig. 13 is a side elevational view of an electromagnetic switch, showing the application of the contact holder shown in Figs. 11 and 12; Fig. 14 is a fragmentary view of a modification of a portion of Fig.

Fig. 15 is a front elevational view of the contact holder shown in Fig. 14, the contact itself being omitted; and Fig. 16 is a view

similar to Fig. 14 but showing the contact fluted as in Fig. 11.

55

Similar reference characters designate similar parts throughout the various views.

Heretofore it has been the practice to provide contact holders comprising spring or screw clamps for holding the contact in firm electrical connection with the electric conductors, but more or less trouble has been experienced, for the reason that the carbon contacts become loose in the holders and then make poor electrical connection, which results in overheating of the carbon and its holder. In some instances the vibration of the holder and its contact, due to the continuous operation of the switch, is sufficient to cause the contact to drop out of its place.

70

It is among the special objects of my invention, not only to lessen the cost of production of contact holders, but also to render them much more efficient, in that each time that the electric switch is operated the contact is wedged more tightly in place, thereby maintaining good electrical connection and the consequential effects.

In Figs. 1 and 2 I have shown a contact holder H which comprises the stem 1, intended to extend through the controller board B and held in place by the nuts 2, 2, between which may be connected a terminal or conductor 33. At its outer or front end the stem 1 is provided with a slot 24, and through the holder H, transversely of said slot, extends a bolt R with a nut 17 on its threaded end, as shown in Fig. 1. A web 28 fitting in a slot in the board may be used to prevent rotation of the holder. Now, if the inside faces of the jaws 8, 8 are such that the contact C may be slipped in between them from either side of the holder H, it is evident that if the holder and the contact expand unequally, or if the nut 17 becomes loose, the contact C will make poor electrical connection, and in some instances drop out of its place. As shown by the dotted lines 25 in Fig. 1, I have changed the shape of the jaws 8, 8 so that the opening at one side of the contact holder is greater than the opening on the other side of the holder. The contact C is correspondingly shaped, but it will be seen that the contact can be placed into the holder from only one side. Preferably the wider opening should be at the top

100

105

so that the holder will appear as indicated in Fig. 2.

In Fig. 2 I have shown connected rigidly to the board B an alternating current magnet M, having an armature A which is pivoted at 23 and is limited in its downward movement by the buffer stop S. The armature is shown in the position it would occupy when the magnet M is energized. At this time the spring 13 holds the lever L in such position that the contact 3 engages the contact C and current may flow from the conductor 33 through the stem 1, holder H, contacts C, 3, and conductor 14 to the apparatus to be controlled. When the magnet M is deenergized, the weight of the armature A causes the same to fall and act against the adjustable abutment 11 to move the lever L on its pivot P against the action of the spring 13, and open the switch comprising the contacts C and 3. It will be seen that each time the magnet is energized and the armature A drawn to its attracted position, the spring 13 causes the contact 3 to strike a blow against the contact C. This blow is directed substantially perpendicularly against the contact C, but a component of the force is exerted to wedge the contact C more firmly in its socket, that is, the tendency will be to move the contact C downwardly from the wider to the narrower portion of the holder H.

By the use of the contact holder shown in Fig. 1, the resiliency of the stem 1, due to the slot 24, will maintain the jaws 8, 8 in contact with the carbon C, through a certain range of difference of expansion of the holder and the carbon, even when the carbon may be placed in the holder from either side. Therefore by making the opening on one side of the holder smaller than on the other side, an additional advantage is obtained by reason of the wedging principle. When the carbon is clamped in position and the wedging action is taken advantage of, it is not necessary that the holder H be fastened to the board B so that the sides of the holder H will be vertical.

In Fig. 3 I have shown a wedge-shaped contact C in a holder H' without any means for clamping the jaws of the holder against the contact. I have, however, shown a cotter pin R' extending through brackets 26, 26 of the holder H' and across the larger space between the jaws, so that after the contact is placed in the holder loosely it will be retained in such position and the contact holder with the contact therein may be stripped or placed in proper position on the controller board without taking care that the contact fits tightly in the holder. Furthermore, it will be immaterial in what position the contact holder is placed on the board, for any blow striking squarely against the contact will immediately result

in the same being wedged tightly in the holder with a firm electrical connection, and such connection is maintained by subsequent operation of the electric switch, for each time the latter operates the tendency is to more tightly wedge the contact in place. This will be more evident from an explanation of Fig. 4, where it will be seen that the front face 9 of the holder itself is inclined from one side to the other so that the contact C will slide along this inclined face into the narrower portion of the socket whenever the contact C is struck by the other contact of the switch.

As indicated in Fig. 4, the contact holder H' is provided with a stem 1 which is screw-threaded at the end opposite the holder to receive the nuts 2, 2. The movable contact 4 may be provided with a stem 5 extending through an insulating bushing 7 carried at the outer end of the lever L. The end of the stem 5 opposite the contact 4 is screw-threaded to receive the nuts 6, 6, one of which bears against the washer 20 to hold the contact 4 rigidly in place with respect to the lever L. Between the two nuts may be clamped the terminal of the conductor 14.

Fig. 5 is a plan view of Fig. 4, the dotted lines showing that the lower portion of the contact socket is narrower than the upper portion. This will be clear by considering this view in connection with Figs. 3 and 4. Fig. 1 by its dotted lines also shows that the lower portion of the contact socket is narrower than the upper portion and inclined downwardly toward the back of the body of the holder.

In Fig. 6 I have shown a holder H'' with a contact C' therein, the space between the jaws 10, 10 being wider than the space between the portions 9, 9. The contact C' is here shown substantially square. The bottom of the socket, or its face against which the bottom of the contact C' bears, is also inclined toward the back of the body of the holder, so that when the contact C' is struck a blow the tendency will be to force the same backwardly and to the left, as viewed in Fig. 6, thus wedging it more tightly in place. This form is intended to illustrate that if the contact C' is once tightly fitted in place the holder need not be provided with any means for keeping the carbon from falling out, its position on the board being immaterial, except that when a square contact is used it should be placed in such a position that when the other contact of the switch engages the same there will be a maximum area of contact.

Fig. 7 is a view similar to Fig. 2, but shows the application of the modification illustrated in Fig. 6. The holder is shown with a plurality of wedge-shaped sockets, in this instance three, so that the movable contacts are all electrically connected to

gether and to the conductor 14. The fixed contacts may also be provided with wedge-shaped sockets and may be connected together electrically or be electrically independent.

Fig. 8 shows a plurality of spring-pressed holders H'', each provided with a wedge-shaped socket and a correspondingly shaped contact C'. In this instance the upper end 10 of the lever L carries a single holder with a plurality of wedge-shaped sockets for the contacts C'. Figs. 7 and 8 are merely to show various applications to which the invention may be put. Obviously the invention 15 may be used to advantage in many other connections and other types of electric switches, with alternating current and direct current. The stem 1' may be square in cross-section to prevent rotation of the contact holder.

In Figs. 9 and 10 I have shown a cylindrically-shaped holder H''' provided with lateral openings 21. This holder is cup-shaped, and the bottom thereof on the inside at 16 is of less diameter than the outer portion thereof at 15, so that a contact snugly fitting in this cup will have the shape of a frustum of a cone. The holder may have a slot as indicated at 22 in Fig. 10, and also wings or projections 18, 18 for receiving a bolt R, so that after the contact is placed in position it may be clamped tightly to the holder by turning the nut 17'. Now, it is evident that when this cup-shaped 35 contact holder and the frusto-conical contact therein is embodied in the switch shown in Fig. 13, such contact will be wedged more tightly in place each time the switch is permitted to be closed.

In order to insure non-slipping of the contact from its holder, I have shown the inner portion of the contact fluted spirally as indicated at 27 to fit corresponding projections on the inner walls of the holder, as indicated in Figs. 10 and 12. It will be seen that with this arrangement the tendency will be for the contact to rotate in its socket when it is wedged more tightly in place, and by reason of the greater surface 50 and the spiral fluting a greater frictional resistance is obtained. This friction may be sufficient to permit the omission of the clamp comprising the wings 18, 18, the bolt R'' and the nut 17'. This form of contact holder and contact is shown in Figs. 11 and 12.

In Fig. 11 I have shown the contact 4 spring-pressed, the spring 19 being held in place at the outer end of the lever L without coming in contact with any portion of the electric switch. This is for the reason that the insulating bushing 7 intervenes. The advantage of this arrangement is that heat from the contact 4 is not transmitted 65 to the spring to lessen its resiliency. It

will also be seen that the metal sleeve 28 slides through the opening in the lever L so that the insulating bushing is not subjected to wear. It should be observed, however, that when spring-pressed contacts are used 70 the insulating bushing is not so important when the wedge-shaped socket holder is used, for in the latter event the heating at the switch contacts is reduced to a minimum.

In Fig. 14 I have shown a cup-shaped holder H'''' provided with lateral openings 21 and a socket, the mouth of which at 15' is larger in diameter than the bottom at 16' and is inclined with respect to the axis of the stem 1. The contact C''' is correspondingly shaped. With this arrangement the contact will be forced into the narrower portion of the holder and also to one side thereof with a wedging action, by reason of the narrower space at the bottom 80 and the inclination with respect to the axis of the stem 1. Fig. 15 shows a front view of the holder with the contact omitted. If desired, the cross-sectional area of the contact and the socket may be irregular as 90 shown in Figs. 9, 10 and 11 so that rotation of the contact will be prevented.

Fig. 16 is in many respects similar to Fig. 14, but showing the contact C''' fluted at 27 similar to the fluted contacts C' of Figs. 9 and 11.

From the foregoing description it will be seen that I have provided a very simple contact holder with inner wedging surfaces. The contact may be clamped in the holder as 100 shown in Figs. 1, 9 and 10, or it may be locked in its socket between the converging jaws by means of a cotter pin, as indicated in Figs. 3, 4 and 5. In some instances the holder may be cup-shaped, as shown in 105 Figs. 9, 11 and 14, wherein an opening 21 is provided for the insertion of an implement to pry out the contact when it is desired to remove the same. Such opening also permits the insertion of the contact with facility, as no air is then confined and put under pressure tending to release the contact. It should be noted that in Figs. 1 to 110 8, inclusive, and in Figs. 14 and 15 the inner wedging surfaces are inclined rearwardly, 115 that is, inclined toward the back of the holder with respect to the axis of the stem or the plane of the face of the contact. During the operation of switch mechanism embodying any form of my invention the 120 contact is wedged more tightly in place whenever struck squarely on the face; nevertheless, the contact may be easily removed by loosening the clamp, if any, or by simply striking the block on its narrower exposed 125 side, or by prying it out if the cup holder is employed.

I wish it to be understood that I do not desire to be limited to the exact details of construction shown and described, for ob- 130

vious modifications will occur to a person skilled in the art.

Having thus fully described my invention, what I claim and desire to have protected by Letters Patent of the United States is:—

1. In an electric switch, the combination with a cup-shaped socket irregular in cross-section and tapering toward its bottom, of a frusto-conical contact in said socket, and means for clamping the socket on the contact.
2. In an electric switch, the combination of a contact, and a cup-shaped socket for receiving and holding said contact, said socket having a lateral opening for the insertion of an implement to remove the contact.
3. In an electric switch, the combination of a substantially spirally fluted contact block, and a correspondingly shaped holder therefor.
4. In an electric switch, the combination of a contact having a flat face and an extension frusto-conical and inclined with respect to said face, the smaller end of said extension being remote from said face; and a holder provided with a stem whose axis extended is substantially perpendicular to the plane of said face.
5. In an electrical switch, the combination of a stationary contact and a coöperating movable contact block having abutting faces, a holder for the said contact block provided with a socket having the lateral faces there-

of fluted and slightly convergent, the said contact block being fitted in said socket and having lateral faces correspondingly convergent, whereby the impact of the contact block against the said stationary contact when the switch is operated will tend to drive the contact block more tightly into its socket.

6. In an electrical switch, the combination of a frusto-conical contact block, and a holder having a correspondingly shaped socket to receive the block, the contacting surfaces of said block and holder being irregular in outline to prevent rotation of the contact block in its socket.

7. The combination of a contact block formed with a plane contact face, a holder for said block provided with a stem perpendicular to the said contact face and formed with a socket having its axis inclined to said stem.

8. The combination of an electrical contact holder provided with a stem and formed with a frusto-conical socket the axis of said socket being inclined to the said stem, and a contact block fitting in said socket.

In testimony whereof, I have signed my name to this specification in the presence of two subscribing witnesses.

AUGUST SUNDH.
